2,468,198

MAGAZINE TYPE MAGNETIC RECORDER
WITH MULTIPLE LANE TAPE AND TRAV-
ERSING TRANSDUCER

Herman S. Heller, West Los Angeles, Calif.

Application August 3, 1945, Serial No. 608,734

24 Claims. (Cl. 179—100.2)

1

This invention relates generally to sound recording and reproducing machines of the type employing a long record tape. In most of its aspects the invention is particularly applicable to sound recording and reproducing machines of the magnetic tape type, and will hereinafter be described primarily in that connection, though without necessary limitation thereto since certain features of the invention may have application to equipment utilizing record tapes of other than magnetic character.

The invention is directed particularly to recording and reproducing machines of the type utilizing a multiplicity of recording lanes spaced transversely across the tape. These lanes are normally used consecutively, with the tape traveling first in one direction and then in the other between a pair of tape reels. One advantage inherent in multiple lane recording resides in the fact that the tape may be much shorter for a given duration of recording time. For instance, assuming eight lanes across the tape, the tape need only be one-eighth as long as the tape or wire necessary for an equivalent recording time in single lane recording. An accompanying advantage is that the time duration for running the tape from end to end is reduced by the same factor, for example, by a factor of eight, so that the rewinding time is much reduced. Reference may be had to Patent No. 2,213,631, issued September 3, 1940, to Herman S. Heller and Leo G. Butler for disclosure of multiple lane recording of one type, wherein a set of recording and erasing magnets is provided for each lane of the tape. Reference is also had to Patent No. 2,275,961, issued March 10, 1942, to Herman S. Heller, for disclosure of multiple lane recording of another type, wherein but one set of magnets is provided, and provision is made for effecting relative transverse movement between said magnets and the tape whereby recordings may be made on the different transversely spaced lanes thereof. The present invention may be regarded generally as providing improvements in multiple lane recording and reproducing apparatus of the general type disclosed in said patents. And while the present invention in certain of its aspects is broadly applicable to both of the aforementioned types of multiple lane recording, it is here specifically and illustratively disclosed in the form wherein but one set of magnets is provided and said set of magnets is arranged for relative transverse movement across the tape for selective or successive cooperation with the various recording lanes thereof. In certain specific respects, the invention deals with improvements

2

in the last-mentioned class of multiple lane recording apparatus.

Magnet recording and reproducing machines have previously been known in which the reels and tape guides are incorporated in a portable magazine arranged for quick detachable connection to the main frame of the machine, which latter contains the drive motor, certain driving gear, and sometimes carries the magnets. The act of mounting this magazine on the main frame automatically engages the driving gear with the reels and brings the tape into operative relationship to the magnets. In certain aspects the present invention is concerned with improvements in machines of the class having such a magazine.

Certain specific objects of the invention are as follows: to provide a means for automatically engaging and disengaging the tape from certain drive rolls permanently supported on the main frame of the machine as the magazine is mounted on or removed from the latter; to provide an improved means for closing and opening the magnets on the tape as the magazine is mounted on or removed from the main frame; to provide improvements in means for guiding the tape accurately through or past the magnet unit; to provide improved means for moving the magnet unit step-by-step transversely across the tape for cooperation with successive lanes thereof, including the provision of locking means for assuring that the magnet unit will always be positioned precisely and unwaveringly in alignment with any selected record lane; and to provide improved manually operable means for locking and unlocking the magazine on the machine, and simultaneously therewith moving the tape into operative relationship with the driving rolls and the magnets.

With this preliminary discussion in mind, the invention will be most readily understood by referring at once to the following detailed description of one illustrative embodiment thereof, reference being had to the accompanying drawings, in which:

Figure 1 is a plan section of a sound recording and reproducing machine in accordance with the invention taken on line 1—1 of Fig. 2;

Figure 2 is a front elevation thereof;

Figure 3 is a view somewhat similar to Fig. 1, but considerably enlarged, and with the reels and also the portion of the machine below the magazine omitted;

Figure 4 is a view similar to Fig. 3, but showing a different position of the parts;

Figure 5 is a section taken on broken line 5—5 of Fig. 3;

Figure 6 is a fragmentary vertical section taken on line 6—6 of Fig. 3;

Figure 7 is a detail taken as indicated by line 7—7 of Fig. 3;

Figure 8 is a section taken as indicated by line 8—8 of Fig. 2;

Figure 9 is a plan view of mechanism for locking the removable magazine to the machine, moving the tape to and from operative engagement with the driving rollers, and for closing the magnet unit on the tape, together with manually operable mechanism for operating said members;

Figure 10 is a view similar to Fig. 9 but showing a different position;

Figure 11 is a side elevation of a portion of the manually operable mechanism appearing in plan in Figs. 9 and 10;

Figure 12 is a vertical section taken on line 12—12 of Fig. 3;

Figure 13 is a section taken on broken line 13—13 of Fig. 12, the near magnet head being omitted;

Figure 14 is a section taken as indicated by line 14—14 of Fig. 13;

Figure 24 shows schematically a typical electrical circuit for the machine;

Figure 25 is a plan view of certain modifications which may be incorporated in the magazine, the magazine except for such modifications being understood to be entirely similar to the one originally described; and

Figure 26 is a detail section taken on line 26—26 of Fig. 25.

The illustrative machine comprises a motor unit embodying a main frame or housing 1 having a top plate 2, and a relatively flat reel-carrying unit or magazine 3 detachably mounted on said top plate 2. Magazine 3 embodies a frame in the form of a container, preferably of plastic, and comprising bottom wall 4 adapted to rest on housing top plate 2, and a removable cover comprising top 5 and side wall 6, the lower edge of the latter being adapted to seat on a marginal upwardly facing shoulder 7 on bottom wall 4. As shown best in Fig. 5, wall 4 has a short positioning flange 8 just inside side wall 6. Set into and projecting forwardly from flange 8, on the forward side of the machine, are a pair of pins 9 which are engageable in corresponding apertures in the side wall 6 of the removable cover. The other side of the removable cover 5 carries a pin 10 engageable in an aperture in a flat spring 11 secured to the underside of wall 4 and extending upwardly as shown in Fig. 12.

It will be evident that the cover may be removed by moving spring 11 out of engagement with pin 10, and then tilting the cover upwardly and disengaging it from the pins 9 at the other side.

The bottom wall 4 of magazine 3 has a plurality of apertures 12, here three in number, adapted to receive positioning pins 13 set into and projecting upwardly from top plate 2 of main housing 1. Means later to be described are provided for locking the magazine 3 to these positioning pins 13.

As shown best in Fig. 1, the two reels 14 and 15 for the record medium, here a magnetic tape 16, are positioned at opposite ends and at the forward side of the magazine 3. In its course of travel between the two reels, the tape passes over and between a pair of drive rolls 17 and 18, preferably rubber faced, and positioned on axes which are in a line parallel to the line joining the axes of the reels, and spaced somewhat rearwardly and inwardly of the reels. The stretch of tape between the two rolls 17 and 18 passes between two blocks 19 and 20 constituting the magnet head and understood to carry the later described translating and erasing magnets. The tape is formed with loops 21 and 22 between the two reels and the respective drive rolls 17 and 18, and these loops pass around semi-cylindrical guides 23 and 24 (Figs. 3 and 12). Each such guide consists of a semi-cylindrical block 25, about which is clamped a felt strip 26, designed to smooth and stabilize the travel of the tape. Each block 25 has guide flanges 27 for the edges of the tape, and is mounted on a stationary plate 28 secured to a slightly elevated platform 29 formed on wall 4 (see Fig. 20).

Bottom wall 4 of magazine 3 is formed with apertures 30 to receive with clearance tape driving rolls 17 and 18. As shown best in Fig. 5, each of said tape driving rolls is mounted on a shaft 31 journaled in bearing housing 32 carried by and secured to top wall 2 of housing 1, the shaft 31 having an extension 33 below housing 32 which carries a pulley 34 for a pair of drive belts 35, to be more particularly referred to hereinafter. Bottom wall 4 of magazine 3 also has openings 36, surrounded by upstanding flanges 37, to receive with clearance reel supporting and driving drums 38, the latter being formed on the upper ends of shafts 39 journaled in bearing housings 40 secured to the under side of plate 2, and driven through over-running or one-way clutches 41 and pulleys 42 from belts 35. These over-running clutches may be of conventional character, and incorporate frictional slip devices also of well known type. It is deemed unnecessary to illustrate or describe the specific details of such devices as they and their functions are well known in the art. For one example, see United States Patent No. 2,209,582 to Ross. It may however be stated that the one-way clutches drive the tape in one direction only, for the purpose of winding up the tape, one clutch driving and the other running freely for each direction of the tape. The frictional slip feature is a common expedient employed to permit slippage in the drive when or if the roll of tape on the driven take-up reel becomes so great in circumference that the reel tends to wind up the tape at a faster rate than it arrives from the positively driven drive rolls.

Bottom wall 4 of magazine 3 also is formed with an aperture 43 adapted to receive with suitable clearance magnet carrying blocks 19 and 20, un-

derstood to be supported and to project upwardly from main housing 1.

The drive motor 44 is mounted in a vertical position in housing 1, and drives main belt drive pulley 45 through suitable enclosed reduction gearing. The aforementioned belts 35 are threaded about the several pulleys 34, 42, and 45 as shown clearly in Fig. 8. Thus the two drive rolls 17 and 18 are directly driven from motor 44 through belts 35, while the two reels 14 and 15 will be alternately driven in the proper direction through the described one-way clutches 41 depending upon the direction of drive of the belts 35. It will of course be understood that the reel toward which the tape is fed by the drive rolls 17 and 18 will always be the one which is driven through its corresponding one-way clutch, the other reel simply idling at such time.

Each of the aforementioned reel-supporting and driving drums 38 (Fig. 5) extends through and somewhat above the surrounding annular flange 37, and carries a plurality of driving pins 46 receivable in sockets 47 formed in disk 48 press fitted within a socket 49 formed in the hub 50 of the reel. The reel has a central or axial sleeve 52 which is engaged by the rounded end of a spring pressed plunger 53 working in a mounting 54 secured to the under side of container top 5. When the magazine 3 is removed from the housing 1, hub disk 48 of course separates from driving drum 38, and the reel is pressed downwardly by spring pressed plunger 53 to rest on the upper end of flange 37. It will of course be understood that when the magazine 3 is mounted back on the machine, sockets 47 are engaged with drive pins 46, and as the magazine goes into position, the reel is relatively elevated against spring pressed plunger 53 to the position shown in Fig. 5.

Magnet block 20 is tightly secured to a platform 55 secured in turn to a head 56 on the upper end of a post 51, and the opposed magnet block 19 is mounted on platform 55 for movement toward and from block 20. Horizontal guide pins 58 set into block 20 and slidably received in corresponding apertures in block 19 assure precise alignment of the two blocks at all times. Magnet block 20 has at the bottom a projecting shelf portion 59 receivable in an undercut or notch 60 in the bottom of block 19, and springs 61 set into the opposed portions of said parts tend to separate the blocks from one another.

Each of the blocks 19 and 20 contains a plurality of electromagnets 62 (Figs. 14 and 16). Each of these electromagnets 62 contains an axial magnetic pole piece 63 of rectangular cross section. In the embodiment here shown, this pole piece is embedded in a plastic shell 64, of square cross section, which is slidable longitudinally or axially in an aperture of corresponding cross section extending through the electromagnet. At the forward end of the shell 64 the tip of the pole piece is exposed so that it may engage the face of the tape. The tip portion of the pole piece may typically be of a width of the order of .023 inch, while back of the extreme tip a distance of approximately $\frac{1}{2}$ ", the width may be increased advantageously to about .055 inch. The pole piece may be of a thickness of $1\frac{1}{2}$ mils. To increase the cross section of the magnetic circuit, a magnetic lamination 65 is placed along side the wider extent of pole piece 63 (Fig. 23). The plastic shell 64 is made hard enough that it will wear at substantially the same rate as the pole piece. The rear end of the shell 64 is engaged by a spring

66 which urges the pole piece into light presural engagement with the tape. In the present embodiment of the invention, each of blocks 19 and 20 contains three of the electromagnets 62, arranged in succession longitudinally of the tape, it being understood that corresponding magnets in the two blocks 19 and 20 are in direct axial alignment with one another. In a preferred arrangement, the two outside magnets 62 are utilized for erasing purposes, and the center magnets are translating magnets for recording and/or reproduction.

A feature of the present invention is the provision of a tape guide comprising a pair of separable guide plates 67 and 68 normally in face to face engagement and adapted to guide the tape during its travel between the two magnet blocks 19 and 20. Thus plate 67 is formed with a tongue 69 and plate 68 with a corresponding groove 70, a longitudinal slot or guide way for the tape being formed between the face of said tongue and the bottom of said groove. For a tape of .002 inch in thickness, the guide way may be .008 inch in depth. The guide way is of such width as will receive the tape for free sliding movement therethrough. The fit is such, however, that the tape will be closely guided and will be precisely positioned by the device. Plate 68 has at the bottom a projecting foot 71 which underlines the lower edge of the plate 67, and engages downwardly against and is accurately positioned by a pair of studs 72 mounted in the top plate 2 of the housing 1, as shown best in Fig. 16. The plates 67 and 68 are pressed down firmly against the positioning studs 72 by means of a flat spring 73 secured to the upper edge of the plate and engageable with the top wall of the magazine.

The two guide plates 67 and 68 are notched at the bottom, as indicated at 74, to clear the guide pins 58 and spring 61, said notch extending the full length of the magnet blocks, as appears in Fig. 16. The downwardly projecting legs formed by the provision of this notch engage over opposite ends of the shelf portion 59 of the block 20 in such manner as to confine the plates 67 and 68 against longitudinal movement relative to the magnets, all as may be clearly understood by inspection of Fig. 16.

The end portions of tape guide plates 67 and 68 are provided with vertically elongated slots 75 through which project horizontal headed studs 76 set into posts 77 extending upwardly from bottom wall 4 of reel carrier unit 3, coil springs 76a being provided on said studs between the heads thereof and the plates, as clearly indicated in Fig. 3. The vertical elongation of these apertures 75 (see Fig. 16) assures that they will not participate in the vertical positioning of the plates 67 and 68, but the fit horizontally is relatively close and the studs 76 therefore serve to accurately position said plates in a horizontal direction. They also serve to carry these plates when the reel carrier unit is removed from the machine, at which time the plates 67 and 68 will of course be moved by spring 76a against the posts 77 (Fig. 4). It will be evident that when the magnet blocks 19 and 20 are separated (Fig. 4), or at any time that the magazine 3 is off the machine, the plate 68 may be separated from the plate 67 against the yielding opposition of springs 76a, and the tape guide way thus opened to permit insertion or removal of the tape.

As shown best in Fig. 16, the guide plates 67 and 68 are provided with vertically elongated apertures 78 extending transversely across the tape

and providing clearance for the pole pieces of the magnets in all vertical positions thereof.

It has previously been mentioned that three positioning pins 13 mounted on top plate 2 of main housing 1 are receivable in apertures 12 in bottom wall 4 of magazine 3, and that means co-acting with these positioning pins locks the magazine 3 in position on the machine. These provisions will next be described. Reference to Fig. 3 will show that one of these pins 13 is located between the two reels and near the front side of the machine, and that the other two are equally spaced on opposite sides of the transverse center line of the machine, and positioned just outside the driving rolls 17 and 18, closely adjacent the slanting end walls of magazine 3. Each of the pins is provided with an annular reduction or neck 78a (Fig. 6) which is engageable by a co-acting locking means carried by the magazine. In the embodiment of the invention here shown, this locking means comprises a longitudinally reciprocative arm or bar 79, formed of sheet metal, extending along the transverse center line of the magazine and provided near one end with an elongated slot 80 which receives the centrally located pin 13. One end of this slot 80 is engageable with the neck 78 of said pin 13, as shown in Figs. 3 and 6, whereby the magazine 3 is locked against separation from main housing 1. When the arm 79 is shifted from the position of Fig. 3 to that of Fig. 4, it is disengaged from pin 13. Underlying the other end portion of the member 79, and secured thereto as by riveting or welding, is a cross member 81, the two extremities 82 of which, working under guides 83, project towards the two remaining pins 13, and are engageable with the reduced neck portions thereof in the locking position of the mechanism (Fig. 3). The magazine is thus locked at three points when the described locking device is in the position of Fig. 3 and is released for removal in the position of Fig. 4. The member 79 is slidably supported on a slightly elevated boss or table 84 formed on wall 4 near one end portion thereof, and is received and supported within a guide way 85 formed in the aforementioned platform 29 (see Fig. 20). The arm 79 is also supported, in the area of its slot 80, in a guide way 86 formed in a slightly elevated table 87 formed on the wall 4 (Figs. 6 and 21) a strap or bridge member 88 mounted on the member 87 overlying arm 79 and being apertured at 89 to receive pin 13.

Attached at one end to plate 87 is a spring arm 90 carrying a pin 91 which is engageable in an aperture 92 in arm 79 when the latter is in the position of Fig. 4. A pin 93 projecting upwardly from top 2 of main housing 1 and receivable through a suitable aperture in the bottom of unit 3 (Fig. 21) is engageable with the free end of this spring arm 90 when the magazine 3 is mounted on housing 1, acting at such times to lift said arm to the position of Fig. 21, wherein pin 91 clears the upper side of arm 79. When the arm 79 is moved to the unlocked position of Fig. 4, pin 91 registers with aperture 92, and when the magazine is then lifted from housing 1, spring arm 90 moves downwardly flush against plate 88, causing pin 91 to engage in aperture 92 and thus lock the arm 79 and the various members controlled thereby in the position of Fig. 4.

The means for shifting the arm 79 between the positions of Figs. 3 and 4 will next be described. Arm 79 is formed with a cross slot 94, which receives a crank pin 95 projecting upwardly through an arcuate slot 96 in wall 4 from a crank disk 97

rotatably mounted in the top of main housing 1 as shown in Fig. 6. Projecting downwardly from crank disk 97 is a pin 98 carrying a crank arm 99, and the latter is pivotally connected by link 100 to a crank arm 101 on a shaft 102 rotatably mounted in the top of housing 1, said shaft 102 having connected thereto an operating handle 103 which is at an elevation just above the upper side of the magazine 3 (Fig. 2). Operation of handle 103 between the two positions indicated in Figs. 9 and 10 acts through arm 101 and link 100 to move crank arm 99 and crank pin 95 between the positions of Figs. 9 and 10, the crank pin 95 thus operating to shift the locking device between locking position (Fig. 9) and unlocked position (Fig. 10).

The described movement of arm 79 is also utilized to perform other functions, one of which is to shift the removable magnet block 19 into operative position as the magazine 3 is locked to the machine. For this purpose, arm 79 has at its rearward end spaced extensions or legs 104 terminated by upwardly turned feet 105 adapted to engage the side of the magnet block 19 to move it from the open position of Figs. 10 and 4 to the closed position of Figs. 3 and 9. It will be recalled that the block 19 is normally urged to separate from the block 20 by virtue of the springs 61, and the block 19 accordingly moves away from block 20 under the influence of these springs when arm 79 is shifted to the position of Fig. 4 to unlock the magazine. Thus the magazine being unlocked, the magnet blocks 19 and 20 are automatically separated; the tape guide unit consisting of plates 67 and 68 backs up against the posts 11 at such time, to a position free and clear of the pole pieces, and the magazine may be lifted from the machine.

The other function performed by the arm 79 in moving longitudinally between the positions of Figs. 3 and 4 is to move the tape into and out of operative engagement with the drive rolls 17 and 18. A pair of links 106 are pivotally connected to arm 79, as at 107, and said links 106 are pivotally connected to links 108, the latter being pivotally connected at 109 with a pair of swinging arms 110 that are in turn pivotally mounted at their ends on magazine bottom wall 4 near the forward edge thereof, as shown at 111. Arms 110 extend under and beyond the stretch of the tape extending between guides 25 and the corresponding drive rolls, and have upwardly turned projections 112, surrounded by rubber sleeves 113, adapted for gripping engagement with the tape. The other ends of links 108 are pivotally connected to arms 114 arranged for longitudinal movement with reference to arms 110. Thus, the arms 114 may have longitudinal slots 115 receiving pins 116 projecting upwardly from arms 110. The forward ends of arms 114 are provided with upwardly turned portions 117, enclosed by rubber sleeves 118, adapted to grip the opposite face of the tape, i. e., the face opposite to that gripped by the member 112. That is to say, the tape passes between the two members 112 and 117, and may be gripped or pinched therebetween. In the position of Fig. 3, the members 112 and 117 are both separated from the tape. When arm 79 is moved from the locking position of Fig. 3 toward the release position of Fig. 4, links 106 at first are restrained against swinging outwardly by an interconnecting spring 119, and function to swing links 108 so as to move arms 114 longitudinally relative to arms 110, thereby causing tape gripping elements 117 to

engage the tape and press it firmly against elements 112. In this movement, the elements 117 and 112 secure a firm grip on the tape, the rubber sleeves assuring a non-slipping engagement. The members 117 and 112 having thus closed on the tape, further travel of arm 19 toward the position of Fig. 4 causes the links 106 to spread further apart, and, acting through links 108, to swing the two arms 110 outwardly. Thereby the tape, gripped between elements 112 and 117, is moved outwardly and away from drive rolls 16 and 17, as to the position of Fig. 4, from which it will be observed that the tape has entirely cleared the drive rolls. The parts then being in the position of Fig. 4, with the magazine unlocked from the machine, and the tape being clear of the drive rolls 17 and 18, the magazine may readily be lifted from the machine. Pins 120 set into the bottom of the magazine cooperate in supporting the tape out of contact with the rolls 17 and 18 in the position of Fig. 4.

The aforementioned post 57 which carries the magnet head (Fig. 14) is in the form of a cylindrical shaft provided with a working fit in a bushing 121 set into a frame 122 secured within housing 1, the bushing 121 having at its upper end a head flange 123 resting down on horizontal surface 124 of frame 122. A stud 125 set into the side of frame 122 has at its inner end a reduced pin 126 (Fig. 16) projecting through an aperture 127 in bushing 121 and into a vertical splineway 128 cut in the side of post 57 to prevent rotation of the latter while permitting longitudinal travel thereof. Screwed into the bottom end of post 57 is a stud 129 (Fig. 16) carrying below the lower end of bushing 121 a flange 130 of a diameter somewhat larger than said bushing, and projecting downwardly below the latter is a cam follower pin 131 having a rounded lower end bearing on the periphery of a stepping cam 133. The cam 133 is mounted on a horizontal shaft 134 journaled at opposite ends in depending extensions 135 and 136 of frame 122.

The aforementioned surface 124 of frame 122 is the top surface of a bridge-like member 137, and the latter has, somewhat above the lowermost end of bushing 121, a downwardly facing horizontal surface 138. Surrounding the bushing 121 and engaging this surface 138 is a flat washer 139, and against washer 139 and surrounding bushing 121 is an annulus 140 which serves as a carrier for certain presently described locking devices. This annulus 140 has a reduced downwardly projecting sleeve-like portion 141, and confined between the lower end of the latter and the aforementioned flange 130 is a coil compression spring 142, the latter encircling the lower end portion of bushing 121, and acting downwardly on flange 130 to maintain cam follower 131 in spring-urged engagement with cam 133. The spring 142 thus tends constantly to urge the magnet carrying post 57 in a downward direction, while the cam 133 lifts the post 57 against the yielding opposition of said spring. As clearly appears in Fig. 14, the described annulus 140 is secured to frame bridge 137 by means of long screws 143.

Cam 133 and shaft 134 are rotated, step by step, by a mechanism including a ratchet wheel 144 mounted on shaft 134 and a pawl device 145 reciprocated in a vertical direction by a solenoid 146. Solenoid 146 is mounted on a frame plate 147, hung from frame 122 by means of strap 148. It has a vertically reciprocative plunger 149, to

the upper end of which is secured the horizontal leg of the L-shaped pawl device 145, the vertical leg of which is in the nature of a flat spring having a vertically elongated slot 150 (see Fig. 12) engageable over the successive ratchet teeth 151 of ratchet wheel 144. There being eight recording lanes in the present embodiment of the invention, the ratchet wheel is provided with eight ratchet teeth 151. Between successive teeth 151 are formed slots 152, the defining side walls of which are radial with respect to the axis of the ratchet wheel, and form the ends of the two adjacent teeth. The lands 153 of the teeth 151 are preferably substantially tangential with respect to the radii of the ratchet wheel, as clearly shown in Fig. 16. On the upstroke of the pawl device 145, the pawl slot will ride off the ratchet tooth which it has just previously pulled down, and when the slot 150 has cleared the tooth just above, will spring inwardly as to the position shown in Fig. 16. On the subsequent downward movement, the ratchet tooth thus engaged will be drawn downwardly. To limit the downward travel of the pawl, so that the ratchet wheel will be rotated through substantially 45° (one-eighth of a revolution), a bracket 157 is secured to the upper end of solenoid plunger 149, being arranged to extend upwardly adjacent and somewhat beyond the upper side of the ratchet wheel. A vertically elongated slot 158 is provided to pass the shaft 134. At the top of this bracket 157 is a turned over lug 159, arranged to overlie the ratchet wheel. This lug 159 engages the land 153 of one of the uppermost ratchet teeth when the solenoid plunger and pawl have descended sufficiently to rotate the ratchet wheel through precisely 45°. When the solenoid plunger subsequently rises, a locking pin 160 carried by bracket 157 engages in the lowermost ratchet wheel slot 152 to limit the upward travel of the mechanism, and at the same time to lock the ratchet wheel against rotation. This locking pin 160 has dropped sufficiently to clear the slot 152 by the time the downwardly travelling pawl device 145 strikes the upper end of the ratchet tooth with which it is engaged, so that the ratchet wheel is unlocked just prior to its being picked up by the pawl.

The aforementioned stepping cam 133 has eight constant radius lands 161, of successively increased radii in a clockwise direction, as viewed in the aspect of Fig. 16, and the first to the eighth of these lands, commencing with the one of least radius, are connected by somewhat sharply sloping risers 162. The last or eighth land 161 is connected with the first by a radial drop-off shoulder 163.

It will of course be understood that the solenoid plunger 149 is lowered to operate the pawl device 145 as above described when the solenoid is energized. When the solenoid is de-energized, it is elevated back to its normal position by means of a coil compression spring 164 encircling the plunger 149 between the top of the solenoid and the horizontal leg of pawl device 145 secured to the upper end of the solenoid plunger.

As will be seen from an inspection of Fig. 16, the cam follower pin 131 is in engagement with about the mid-point of a land 161 of stepping cam 133 when ratchet wheel 144 is at rest. Energization of solenoid 146 causes the ratchet wheel to be advanced through a 45° arc, and at about the mid-point of its travel, follower pin 131 is engaged by a cam riser 162 and elevated by one step. It being understood that the cam 133 rotates step-by-step in a counterclockwise direction as viewed in Fig.

16, the cam risers 162 are so dimensioned as to engage and lift the cam follower pin 131, and therefore the magnet head, by a distance equal to the predetermined center-to-center spacing of the recording lanes on the tape. One rotation of the cam, beginning with the first or innermost land in engagement with the follower pin, will accordingly lift the pole pieces of the recording magnets successively to the eight record lanes of the tape, and then drop them to the initial position 10 as the follower pin drops over the radial shoulder 163.

A feature of importance is the provision of a locking device which positively locks the magnet head post 57 against vertical movement following each of the step-by-step elevations thereof and unlocks it during an initial portion of each step-by-step movement of the ratchet wheel. Mounted on shaft 134 is a star wheel 165 having a number of teeth 166 equal in number to the number of ratchet teeth 151, here eight in number. Engaging in the notches between these teeth 166 is a finger portion 167 on the end of the arm 168 of a bell crank 169, said bell crank being rotatably mounted on a stud 170 mounted on frame extension 136 (Figs. 14 and 15). The other arm 171 of bell crank 169 is bifurcated as at 172 to receive an actuating pin 173 projecting radially from a ring 174 rotatably mounted on the reduced sleeve portion 141 of annulus 140, said ring 174 being confined between downwardly facing shoulder 175 on annulus 140 and retaining ring or washer 176 secured to sleeve member 141 as by snap ring 177. Sunk in the upper side of annulus 140 is a diametrical way or slot 178, wherein are slidably positioned a pair of reciprocating locking elements or bars 179, one on each side of the post 57. The inner ends of these locking elements 179 are provided with a plurality of vertically spaced teeth 180, here eight in number, which are engageable in corresponding slots 181 formed in the post 57. For convenience, these slots 181 are herein in the form of annular grooves extending entirely around the post 57, though it will be evident that they need not extend beyond the location of the teeth 180. A sufficient vertical extent of the grooves 181 in the post 57 is provided that there will be a complete set of grooves in opposition to the locking teeth 180 in all vertical positions of adjustment of the post 57. Fig. 16 showing the post 57 in its uppermost position, there are therefore a number of the grooves 181 above the locking element 179 for that position. The center-to-center spacing of the teeth and of the corresponding grooves is made equal to the distance the post 57 is elevated on each actuation of the stepping cam. That is to say, the center-to-center distance of the locking teeth 180 and grooves 181 is equal to the center-to-center distance of the recording lanes on the tape. Each of the locking elements 179 is provided with an angular slot 182 (Figs. 17 and 18) engaged by a pin 183 projecting upwardly from the aforementioned ring 174, the pins 183 reaching through suitable arcuate slots 185 formed in the portion of 65 the annulus 140 directly below the slot 178.

In the position of Fig. 17, the locking elements 179 are in their inward positions, and their locking teeth 180 are inserted snugly in the grooves 181 in post 57, so as to lock the latter rigidly against the slightest vertical movement. Rotation of the ring 174 that carries the pins 183 in a counterclockwise direction as viewed in Figs. 17 and 18 causes the locking elements 179 to be cammed outwardly by the pins 183 working in the angular 70 75

slots 182, thereby removing the locking teeth 180 from slots 181. The ring 174 is so moved by means of its projecting pins 173 and the bell crank 169 earlier described (Fig. 15). The position shown in Fig. 15 is the at rest position, corresponding to Fig. 17, wherein the locking elements 179 are in locking engagement with the post 57. When the ratchet wheel 144 is pulled downwardly by the pawl 145, the star wheel 165 rotates therewith, and during the first few degrees of rotation, the bell crank is moved thereby to the position shown in dot-dash lines in Fig. 15 against the yielding opposition of a flat return spring 185. Thus the bell crank is rocked to release the locking elements 179, i. e., to withdraw said elements to the position of Fig. 18. During this phase of the operation, the cam follower pin 131 is riding on a constant radius land 161. By the time the follower pin 131 encounters one of the risers 162, or alternatively, drops past the shoulder 163, the post 57 has been unlocked by the locking elements 179 as above described, and is free to be elevated. During the latter portion of the 45° rotation of the ratchet wheel the follower pin 131 is again riding on a constant radius land 161 of the cam, and the finger 167 of bell crank 169 is disengaged by the star wheel's tooth and drops again, under the influence of spring 185, into a notch between teeth. Bell crank 169 thus swings back to the full line position of Fig. 15, shifting locking elements 179 into the locking position of Fig. 17.

A lever 186 is pivotally mounted at 187 within a slot 188 in frame member 122 (Fig. 14) and has an upwardly extending arm 189 projecting through opening 43 in magazine wall 4, the upper end of this arm carrying a cross member 190 which bears at its opposite ends plastic or other smooth surfaced buttons 190 adapted to bear on one face of the tape (see also Fig. 3). Similar buttons 191 mounted on brackets 192 secured to plate 28 bear on the other face of the tape, directly opposite the buttons 190. The lower arm 193 of lever 186 engages the projecting operating button 194 of a micro-switch 195. The normal position of the lever 186, as shown in Fig. 14, is such that there is only sufficient spacing between the pairs of buttons 190 and 191 for the tape to pass freely therebetween. The tape is provided near each of its ends with a thickened portion 196 of some extent longitudinally of the tape, as indicated in Fig. 3. When this enlargement or thickened portion passes between a pair of the buttons 190 and 191, the lever 186 is swung a short distance, pressing inwardly on micro-switch button 194 and actuating the latter. This micro-switch is employed in a presently described electrical system to effect a reversal of the drive motor and to perform other functions. It will be understood that the button 194 of the micro-switch 195 is of a conventional spring pressed type, yieldingly urged to occupy the position shown in Fig. 14. Accordingly, the enlargement 196 having cleared the buttons 190 and 191, the spring-urged switch button 194 will return the lever 186 to the position of Fig. 14.

Reference is next directed to Fig. 23, showing schematically an electrical circuit for the machine as above described. Fig. 24 shows two decks 197 and 198 of a switch operated by the previously described ratchet-driven shaft 134, and which appear in side elevation in Fig. 12. Each deck consists of an insulation rotor 199 tightly mounted on the shaft 134, and carrying an electrically conductive collector ring 200 formed on one side with a radially projecting contact 201. This contact

201 is adapted to sweep successively over switch contacts carried by an insulation stator 202 which may be mounted on the machine as in the manner illustrated in Fig. 12. The several switch contacts carried by the stator are spaced 45° apart, and contact is made therewith successively as the shaft 134 is ratchet-driven through successive 45° movements. In addition, there is a brush, numbered 203 in the case of deck 197, 204 in the case of deck 198, mounted on the stator and contacting at all times the collector ring on the rotor.

Figure 24 shows conventionally the three pairs of electromagnets 62, the center pair being translating magnets for recording and/or reproduction, and the two outside pairs being erasing magnets. Each such pair is electrically connected in series, and one end of each pair is grounded, as indicated at 205. The ungrounded end of the translating magnets is connected by lead 206 to the contacts 207 and 208 of a gang switch generally indicated by numeral 209. Opposed to switch contact 207 is a switch contact 210 connected to microphone jack 211, a switch arm 212 being movable to make with either contact 207 or contact 210. Switch arm 212 is connected by lead 213 to the input terminal of amplifier 214. The output terminal of amplifier 214 is connected by lead 215 to movable switch arm 216 adapted to make alternately with contact 208 and with a switch contact 217 opposed to the latter, and said contact 217 is connected by lead 218 to speaker 219. It is to be understood that switch arms 212 and 216 are interconnected so as to move together, being in contact with contacts 210 and 208, respectively, for the "Record" position, and with contacts 207 and 217, respectively, for "Reproduce." In the "Record" position, the microphone, not shown, is connected to microphone jack 211, and a circuit is formed including switch contact 210, switch arm 212, and lead 213 to the input end of the amplifier, and from the output of the amplifier via lead 215, switch arm 216, contact 208, and lead 206 to the translating magnets 62. The magnets are accordingly in circuit with the microphone, and the machine is in condition for recordation. In the "Reproduce" position, the translating magnets are connected by lead 206, switch contact 207, contact arm 212, and lead 213 to the input end of the amplifier, and from the amplifier output via lead 215, switch arm 216, switch contact 217, and lead 218 to speaker 219. Thus the translating magnets are in circuit with the speaker.

The reversible drive motor 44 is indicated in Fig. 24 as of a split phase capacitor type, having four external leads 220, 221, 222, and 223, two for each phase. Numeral 224 designates a source of alternating current power, and one side thereof is connected by lead 225 and lead 220 to one phase of motor 44, the other side of the same phase of the motor being connected by lead 222 and lead 226 to the other side of the power source through motor on-and-off switch 227. A lead 228 branching from lead 225 is connected to a movable switch arm 229, switch contact 230, and lead 231 to motor lead 223 connected to the other phase of motor 44, while the other side of the last-mentioned phase is connected by lead 221, switch contact 232, movable switch arm 233, and lead 234 to power lead 225 leading back to the power source. Thus both phases of the motor are across the power source. The two movable switch arms 229 and 233 are operated by a solenoid 235 which when energized holds them in the position shown in Fig. 24. The switch is of the type such

that when the solenoid 235 is de-energized, switch arms 229 and 233 make with contacts 236 and 237, respectively. Contact 236 is connected to motor lead 221, and contact 237 is connected to motor lead 223. It will be evident, therefore, that when the switch is in the alternative position, that is, with switch arms 229 and 233 against contacts 236 and 237, respectively, the one phase of the motor 44 is reversed in polarity with respect to the other, whereby the direction of rotation of the motor is reversed. Hence, energization and de-energization of the solenoid effects drive of the motor in one direction or the other, thereby accomplishing drive of the tape in one direction or the other.

Solenoid 235 is connected by lead 238 to a movable switch arm 239 of a manual reverse switch 240, switch arm 239 being normally in contact with switch contact 241 connected by lead 242 to alternate stator switch contacts 243 of switch deck 198. The switch rotor being in a position such that its contact 201 is in engagement with one of the switch contacts 243, the circuit is closed via collector ring 200, brush 204 and lead 244. Hence with the rotor of switch deck 198 in any position with its contact arm 201 in engagement with one of the contacts 243, solenoid 235 will be energized and the motor will drive in one direction.

Manual reverse switch 240 includes a movable switch arm 245 and an opposed contact 246, the arm 245 normally being out of contact with contact 246. Switch arms 239 and 245 are interconnected, in such manner that when the manual reverse switch is operated, switch arm 239 breaks from contact 241 and switch arm 245 makes with contact 246. Upon release, the switch returns to the position indicated. Switch arm 245 is connected by lead 247 to the remaining switch contacts 248 on the stator of switch deck 198. Switch contact 246 is connected by lead 249 with movable switch arm 239.

Assuming now that the switches are in the position of Fig. 24, with the motor driving the tape in one direction. If at any time it should be desired to back track along the tape, manual reverse switch 240 is operated. Switch arm 239 is then separated from switch contact 241, so that the switch contacts 243 of switch deck 198 are open circuited. Solenoid lead 238 is at such time connected by a lead 249, switch contact 246 and switch arm 245 to stator contact 248 of switch deck 198, but in the present position of the switch rotor, said contacts are open circuited. Solenoid 235 is accordingly de-energized, and the motor 44 will be reversed in the manner previously described.

Assume next that the switch deck rotor has been shifted into a position wherein its contact 201 makes with one of contacts 248. Solenoid 235 will accordingly be de-energized, since contacts 243 are open circuited. To effect a manual reverse, reverse switch 240 is depressed. Solenoid 235 is now connected by lead 238, lead 249, switch contact 246 and arm 245 to lead 247 and thence to switch contacts 248. The circuit is completed from there through rotor contact 201 and brush 204 to return lead 244. The solenoid is therefore energized, and the result of depressing the manual switch has been to reverse the direction of the motor.

It will thus be seen that as the previously described ratchet and pawl mechanism operates to shift the machine from one recording lane to the next, it at the same time moves switch rotor 198

ahead step by step, thereby reversing the direction of drive of the tape for each shift from one lane to the next. Thus a recording having been completed on one lane of the tape, and the machine operating to shift to the next or adjacent lane thereof, the motor automatically reverses direction so as to drive the tape in the reverse direction, and the recording is thus accomplished on successive lanes with the tape driving in first one direction and then the other. And at any time the direction of rotation of the drive motor may be reversed to back track along the tape without shifting from lane to lane by operation of the manual reverse switch 240, as previously described.

The stator of switch deck 197 has one set of switch contacts 250, and a set of intervening contacts 251, adapted to be swept successively by the switch arm 201 of the corresponding rotor. The contacts 250 are connected by lead 252 to one set of erasing magnets, and contacts 251 by lead 253 to the other set of erasing magnets. A high frequency oscillator 254, which constitutes the source of erasing current, has one output lead 255 connected to brush 203 bearing on the collector ring 200 of the switch deck 197. It will be evident that the oscillator output lead 255 is alternately connected to one set of erasing magnets and then the other as the switch rotor is stepped ahead in consonance with the stepping operation of the previously described pawl and ratchet mechanism. To complete the oscillator circuit to the erasing magnet, the other oscillator output lead 256 is connected to a switch contact 257, contacted by a movable switch arm 258, which latter is connected to ground. The contact 257 and switch arm 258 are a part of the gang switch 209, switch arm 258 making with contact 257 when the switch is in the "Record" position, and opening the oscillator circuit to ground in the "Reproduce" position. Thus during the recording operation, the other oscillator output terminal is connected to ground through the described switch, thereby completing the circuit. Connections are so made that during recording with the tape 16 travelling toward the right, as viewed in Fig. 24, the left-hand erasing magnet will be energized through the switch 197; and with the tape travelling in the opposite direction, the right-hand erasing magnets will be energized through the switch 197. Thus, for either direction of tape travel, the tape encounters first a set of erasing magnets, which obliterates any past history thereon, and then the recording magnet, the remaining set of erasing magnets being open circuited at the time. For the "Reproduce" position of switch 209, the oscillator circuit is open at switch 209.

Fig. 24 also shows the stepping solenoid 146 which actuates the pawl and ratchet mechanism to move the magnet head from lane to lane, as well as, through shaft 134, to move the rotors of switch decks 197 and 198 ahead step by step, as indicated by the dash lines in Fig. 24. The solenoid 146 is shown as connected by one lead 259 to one side of the power source, and by a lead 260 to one side of the aforementioned micro-switch 195 previously described as actuated by the tape. The other side of said micro-switch 195 is connected by lead 261 and lead 225 back to the other side of the power source. The solenoid is thus energized to perform the various functions already described by closure of micro-switch 195, and it has already been described how this micro-switch may be closed by enlargements formed on the

tape near each of its ends. Any other means for operating micro-switch 195 by the tape may of course be substituted.

Referring now to Figs. 25 and 26, I show a magazine having certain features which it will be understood may be added to the magazine previously described. The magazine 3 is in this instance formed of a transparent material, preferably a plastic such as clear Lucite. The reels 14 and 15 are the same as before, but mounted between them inside the transparent magazine is an indicator device 262 embodying an arm 263 pivotally mounted as at 264 on a bridge member 265 and urged by a coil spring 266 to bear constantly on the periphery of the tape roll 267 on one of the reels. Pivotally connected to the front end of arm 263 is a scale sector arm 268 provided with a scale 269 which is visible through the transparent top wall of the magazine. The arm 268 is yieldingly positioned normally in the full line position with respect to arm 263 by means of a spring-pressed detent 270 carried by the arm 268 and engageable in a suitable hole in the arm 263. A fixed indicator line 271 inscribed or engraved on the transparent top wall of the magazine above scale 269 cooperates with said scale 269 and permits the obtainment of reference numerals by which any desired point of the recording on the tape may subsequently be quickly found. To permit the reels to be removed from the magazine, it is necessary to fold the arm 268 against the arm 263, as to the dot-dash position of Fig. 25. Accordingly, the arm 269 is pivotally swung to the folded position indicated, and a hole 272 in arm 263 is at that time engaged by spring-pressed detent 270. Thus, the arm 269 will be yieldingly supported in the position shown in dot-dash lines. A spring 273 mounted within the magazine may be engaged by the end of the arm 263, supporting said arm in a position clearing the reel 15, as will be readily understood.

The drawings and description are, of course, to be taken as illustrative of one present embodiment of the invention, and it will be understood that various changes in design, structure, and arrangement may be made without departing from the spirit and scope of the invention or of the appended claims.

I claim:

1. In a recording machine employing a record tape, the combination of a motor unit embodying a housing, a drive motor in said housing, a rotatable drive roll mounted on and projecting from one side of said housing, means driving said drive roll from said motor, and a separable magazine unit adapted for quick demountable attachment to said side of said housing, said magazine adapted to receive said drive roll, locking means on said magazines for locking said magazines to said motor unit, record tape supporting means within said magazine, and means operable by said locking means for moving said tape into and from a position of peripheral driving engagement with said drive roll.

2. In a recording machine employing a record tape, the combination of a motor unit embodying a housing, a drive motor in said housing, a rotatable drive roll mounted on and projecting from one side of said housing, means driving said drive roll from said motor, and a separable magazine unit comprising a container adapted for quick demountable attachment to said side of said housing, said container having an aperture adapted to receive said drive roll, record tape supporting and guiding means in said container including

means forming a loop around said tape drive roll, and tape engaging means embodying a pair of gripping elements operable to grip opposite faces of said tape at one side of said loop and to move said loop while the tape is so gripped out of or into peripheral driving engagement with said drive roll.

3. In a recording machine employing a record tape, the combination of a motor unit embodying a housing, a drive motor in said housing, a rotatable drive roll mounted on and projecting from one side of said housing, means driving said drive roll from said motor, and a separable magazine unit comprising a container adapted for quick demountable attachment to said side of said housing, said container having an aperture adapted to receive said drive roll, record tape supporting and guiding means in said container including means forming a loop around said tape drive roll, and tape engaging means embodying a pair of gripping elements operable to grip opposite faces of said tape at one side of said loop and to move said loop while the tape is so gripped out of or into peripheral driving engagement with said drive roll, said gripping elements being carried one by an arm pivoted on said container and one carried by and longitudinally movable with respect to said arm.

4. In a recording machine employing a magnetic record tape, the combination of a main housing, a translating magnet unit embodying a pair of opposed separable translating magnets with projecting pole pieces supported on and projecting from one side of said housing, a separable magazine unit comprising a container adapted for quick demountable attachment to said side of said housing, said container being adapted to receive said magnet unit when so attached to said housing, a tape guide means supported in said container and receivable between said separable magnets, said tape guide means embodying a pair of separable guide plates having a longitudinal tape guide way formed therebetween, said guide plates being apertured opposite said pole pieces of said magnets to permit contact of the pole pieces with the tape, and said separable magnets being closeable on said guide plates, supporting pins mounted in said container projecting at right angles to said guide plates through apertures therein which are elongated transversely of the tape guide way, springs on said pins engaging one side of said plates, and abutment means on the other side of said plates engageable by said plates under the pressure of said spring when said magnets are separated, said abutment means supporting said plates in a position of clearance with reference to said pole pieces of said magnets when said magnets are separated.

5. In a recording machine employing a magnetic record tape, the combination of a means supported on said machine for supporting and guiding a record tape for longitudinal movement in a predetermined path, a pair of translating magnets positioned on opposite sides of said tape moving in said predetermined path, step-by-step means for shifting said magnets transversely of said tape to successive positions across the tape whereby recordings may be made on different non-overlapping longitudinally extending lanes of said tape, locking means for positively locking said magnets in each of said successive positions, and means for automatically unlocking said locking means upon each actuation of said step-by-step means.

6. In a recording machine employing a mag-

netic record tape, the combination of a means supported on said machine for supporting and guiding a record tape for longitudinal movement in a predetermined path, a pair of translating magnets positioned on opposite sides of said tape moving in said predetermined path, a pawl and ratchet means for shifting said magnets transversely of said tape to successive positions across the tape whereby recordings may be made on different non-overlapping longitudinally extending lanes of said tape, locking means for positively locking said magnets in each of said successive positions, and means for automatically unlocking and locking said locking means during initial and terminal portions of the movement of said pawl.

7. In a recording machine employing a magnetic record tape, the combination of a frame, a translating magnet unit embodying a pair of opposed separable translating magnets with projecting pole pieces supported on said frame, and a tape guide means accurately positionable in a predetermined fixed operating position between said magnets embodying a pair of separable guide plates extended longitudinally of the tape and formed with a longitudinal tape guide way therebetween which closely guides the edges of said tape, said guide plates being cut away opposite said pole pieces to permit contact of the pole pieces with the tape, and said separable magnets being closeable on said guide plates.

8. A combination as defined in claim 7, wherein in one edge of said tape guide means engages fixed positioning abutment means.

9. A combination as defined in claim 7, wherein in one edge of said tape guide means engages fixed positioning abutment means, and spring means urging said tape guide means against said abutment means.

10. A combination as defined in claim 7, in which means are provided supporting said tape guide plates for movement as a unit in directions at right angles to the plane of the tape during opening and closing movements of said separable magnets.

11. In a recording machine employing a magnetic record tape, the combination of a frame, means supported on said frame for guiding a tape in a predetermined path, a pair of opposed translating magnets with projecting pole pieces positioned on opposite sides of said predetermined path of said tape, means supported on said frame for shifting said magnets transversely across the tape, and a tape guide means accurately positioned in a predetermined fixed operating position between said magnets embodying a pair of separable guide plates extended longitudinally of the tape and formed with a longitudinal tape guide way therebetween which closely guides the edges of the tape, said guide plates being apertured opposite said pole pieces to permit contact of the pole pieces with the tape throughout all transverse positions of the magnets.

12. A separable magazine unit for the record tape of a sound recording machine having a motor unit, a drive motor mounted thereon, and tape drive roll means adapted for peripheral engagement with the record tape mounted thereon and driven by said motor, that comprises: a magazine frame adapted for detachable connection with said motor unit, means on said frame for supporting a record tape, locking means for locking said magazine frame to said motor unit, and means on said frame operative in consonance with said locking means when said frame is positioned on said motor unit for moving said tape

between a position of peripheral engagement with said drive roll means and a position clearing said drive roll means.

13. In a recording machine employing a record tape, the combination of a motor unit embodying a housing, a drive motor in said housing, a rotatable drive roll mounted on and projecting from one side of said housing, means driving said drive roll from said motor, and a separable magazine unit adapted for quick demountable attachment to said side of said housing, said magazine adapted to receive said drive roll, and record tape supporting and guiding means in said magazine including movable tape gripping means engageable with opposite faces of the tape for gripping a portion of said tape and moving it into peripheral driving engagement with said drive roll or backing it off therefrom.

14. A recording machine as defined in claim 1, in which said tape gripping means embodies a pair of gripping elements operable to grip opposite faces of the tape at a point spaced from said drive roll while said tape is in engagement with said drive roll and to move the gripped portion of the tape in a direction to back the tape out of engagement with said drive roll.

15. In a recording machine employing a magnetic record tape, the combination of a main housing, a translating magnet unit embodying a pair of separable translating magnets supported on and projecting from one side of said housing, a separable magazine unit adapted for quick demountable attachment to said side of said housing, means in said magazine for guiding a record tape therein between said two magnets, locking means on said magazine operable to positively lock said magazine to said housing after it has been attached thereto, and means for closing said magnets on said tape by virtue of locking operation of said locking means and for separating said magnets by virtue of unlocking operation of said locking means.

16. In a recording machine employing a record tape, the combination of a motor unit embodying a housing, a drive motor in said housing, a rotatable drive roll mounted on and projecting from one side of said housing, means driving said drive roll from said motor, a translating magnet unit embodying a pair of separable translating magnets supported on and projecting from said side of said housing, a separable magazine adapted for quick demountable attachment to said side of said housing, means in said magazine for guiding a record tape therein past said tape drive roll and between said pair of magnets, and unitary magnet operating and tape moving means operable only after said magazine is attached to said housing to close said magnets on said tape and to move said tape into a position of peripheral driving engagement with said tape drive roll, and also operable to separate said magnets and to back said tape off said driving roll preparatory to removal of said magazine from said housing.

17. In a recording machine employing a record tape, the combination of a motor unit embodying a housing, a drive motor in said housing, a rotatable drive roll mounted on and projecting from one side of said housing, means driving said drive roll from said motor, a translating magnet unit embodying a pair of separable translating magnets supported on and projecting from said side of said housing, a separable magazine adapted for quick demountable attachment to said side of said housing, means in said magazine for guiding a

record tape therein past said tape drive roll and between said pair of magnets, locking means for locking said magazine to said housing after the magazine is attached thereto, and means operable in conjunction with said locking means for supporting said tape in peripheral contact with said drive roll and for closing said separable magnets on said tape only while said magazine is locked to said housing by said locking means.

18. In a recording machine employing a magnetic record tape, the combination of a main housing, a translating magnet unit embodying a pair of opposed translating magnets with projecting pole pieces supported on and projecting from one side of said housing, a separable magazine adapted for quick demountable attachment to said side of said housing, a tape guide means supported by said magazine and receivable between said magnets, said tape guide means embodying a pair of separable guide plates having a longitudinal tape guide way formed therebetween, said guide plates being apertured opposite said pole pieces of said magnets to permit contact of the pole pieces with opposite faces of the tape, and said pole pieces being arranged for relative movement toward and from said apertured guide plates to permit insertion into and withdrawal from said apertured guide plates.

19. In a recording machine employing a magnetic record tape, the combination of a main housing, a translating magnet unit embodying a pair of opposed separable translating magnets supported on and projecting from one side of said housing, a separable magazine adapted for quick demountable attachment to said side of said housing, a tape guide means floatingly supported on said magazine, fixed abutment means on said main housing engaged by the bottom edge of said tape guide means, and spring means on said magazine acting downwardly on said tape guide means to assure accurate positioning thereof against said abutment means.

20. In a recording machine employing a magnetic record tape, the combination of a means supported on said machine for supporting and guiding a record tape for longitudinal movement in a predetermined path, a pair of translating magnets positioned on opposite sides of said tape moving in said predetermined path, step-by-step means for shifting said magnets transversely of said tape to successive positions across the tape whereby recordings may be made on different non-overlapping longitudinally extending lanes of said tape, and locking means for positively locking said magnets in each of said successive positions, said step-by-step means including a ratchet wheel, a pawl for operating said ratchet wheel, a cam operable by said ratchet wheel, and a cam follower for moving said magnets, said cam operating to move said cam follower during an intermediate portion of each movement of said cam, and said locking means operating in consonance with said pawl to move to unlocking and locking positions during the initial and terminal portions of each driving stroke of said pawl.

21. In a recording machine employing a magnetic record tape, the combination of a means supported on said machine for supporting and guiding a record tape for longitudinal movement in a predetermined path, a pair of translating magnets positioned on opposite sides of said tape moving in said predetermined path, step-by-step means for shifting said magnets transversely of said tape to successive positions across the tape

21

whereby recordings may be made on different non-overlapping longitudinally extending lanes of said tape, said step-by-step means including a ratchet wheel, a pawl for operating said ratchet wheel, a cam operable by said ratchet wheel, a cam follower for moving said magnets, and locking means for positively locking said magnets in each of said successive positions.

22. A recording and reproducing machine employing a record tape, including a motor unit embodying a main housing and a drive motor and driving gear powered thereby in said main housing, a separable magazine for record tape adapted for quick demountable attachment to said housing, a pair of translating magnets mounted on said housing to be received in said magazine when said magazine is mounted on said housing, said magazine including means for supporting a record tape therewithin for travel between said translating magnets, tape drive roll means powered by said driving gear and adapted to operate within said magazine to drive said tape past said translating magnets, said magazine also including tape guide means for guiding the tape between said translating magnets, said tape guide means being floatingly mounted in said magazine, and fixed abutment means on said housing engaged by said tape guide means when the magazine is mounted on the housing to accurately position the tape guide means relative to the translating magnets.

23. A machine according to claim 22, including spring means for holding said tape guide means accurately positioned against said abutment means.

24. A machine according to claim 22, in which said tape guide means comprises a pair of guide plates formed therebetween with a longitudinal guideway for the tape and receivable between the magnets, spring means engaging said guide means to position it against said abutment means, projecting spring-urged pole pieces included in said magnets adapted to bear on opposite sides of the tape, said guide plates being apertured opposite said pole pieces to permit engagement of the pole pieces with the tape, and said pole pieces being retractable to permit insertion or removal of the guide plates to or from their position between the magnets.
